UNITED STATES PATENT OFFICE.

THOMAS KOPINSKI, OF ROCHESTER, NEW YORK.

SURFACE-GAGE.

1,135,941.

Specification of Letters Patent. Patented Apr. 13, 1915.

Application filed November 25, 1914. Serial No. 874,007.

To all whom it may concern:

Be it known that I, THOMAS KOPINSKI, subject of the Emperor of Germany, residing at Rochester, in the county of Monroe and State of New York, have invented certain new and useful Improvements in Surface-Gages, of which the following is a specification.

This invention relates to certain new and useful improvements in surface gages.

The primary object of the invention is to provide a gage and scribe having an adjustable needle swingingly mounted whereby the base of the instrument may be moved upon either straight or curved work for scribing either a straight line or a curve while the base may also be moved along the edge of a planer bed or in contact with any slots or grooves therein for the purpose of scribing straight or parallel lines.

A further object is to provide a standard carrying trammel bar adjustably pivoted and slidably mounted upon a disk revolvably engaging the instrument base while the base is provided with an opening adapted to receive the lower end of the standard and forming positioning means whereby the instrument is adapted to seat upon a cylindrical shaft or like piece in a plane parallel with the axis of the piece it engages.

With these general objects in view and others that will appear as the nature of the invention is better understood, the same consists in the novel combination and arrangement of parts hereinafter more fully described, illustrated in the accompanying drawings and set forth in the appended claims.

In the drawings forming a part of this application and in which like-designating characters refer to corresponding parts throughout the several views, Figure 1 is a perspective view of the device. Fig. 2 is a side elevation thereof with the instrument base and the needle bar with its mounting elements shown in section, and having a jointed standard. Fig. 3 is a central transverse sectional view taken through the instrument base with the standard horizontally positioned as illustrated in Fig. 2. Fig. 4 is a transverse sectional view through the standard slide and with the needle bar shown in side elevation, and Fig. 5 is a perspective view of a part of the jointed form of standard.

Referring more in detail to the drawings

a base block 10 is provided which is preferably rectangular in horizontal cross section and may be formed of wood although any other suitable material may be employed. A 60 spirit level 11 is positioned upon the upper face of the base block while a substantially central perforation or bore 12 is provided through the block. A disk 13 having periperal graduations 14 thereon is revolvably 65 mounted above the bore 12 and has its upper face flush with the top face of the block the disk being seated within an annular socket 15 in the top of the block concentric with the bore 12 and is mounted upon anti-friction 70 balls 16 within an annular race-way 17 formed in the block. A set screw 45 is inserted through the disk 13 and engages with in a socket 46 of the block 10 for retaining the disk fixedly positioned when desired. 75 The disk 13 has a central perforation 18 therethrough in alignment with the bore 12 while a standard or ruler 19 is pivotally mounted between spaced triangular shaped ears 20 positioned upon the upper face of 80 the disk 13 and upon either side of the perforation 18, it being noted that a pivot bolt 21 connects said ears and passes through the central longitudinal slot 22 of the standard while a winged nut 23 may be adjusted for 85 retaining the standard in any adjusted position which may be derived by sliding the standard longitudinally as well as moving the same pivotally upon the said bolt 21. A graduated ring 24 is secured to the top of 90 the base block by means of screws 25 and overlaps the disks 13 for preventing its removal from the socket 15 while also furnishing graduations to be employed in connection with the graduations 14 of the disk. 95

A slider or frame 26 is mounted upon the standard 19 being longitudinally slidable thereon and has an adjusting screw 27 whereby the slider may be retained at any adjusted position, while a transverse bolt 28 100 carried by the slider extends through the standard slot 22 and has a winged set nut 29 threaded upon one end thereof by means of which also the slider may be adjustably secured to the standard.

A needle or trammel bar 30 is slidably mounted in a bracket 31 which bracket is rotatably secured to one end of the slider 26. A set screw 32 is carried by the bracket 31 and is adapted to engage the bar 30 when 110 slidably positioned as desired therein. The bracket 31 has a base plate 33 which flatly

engages the end of the slider which is opposite to the end thereof upon which the screw 27 is mounted, while a socket 34 of the slider has an extension 35 of the bracket revolvably 5 mounted therein and retained against removal by a screw 36 positioned with its end extending into an annular groove 37 of the said extension.

The standard shown in Fig. 1 consists of 10 a single piece of material, while in Fig. 2, the standard is shown as consisting of two pieces 38 and 39 secured together by means of screws 40 which provides identically the same form of standard but having additional 15 length, the standard in either event being provided with different length graduations 41 and 42 upon the portions thereof positioned at opposite sides of the slot 22.

From this detailed description of the device 20 it will be seen that the base block may be leveled upon the planer bed or pattern by means of the spirit level 11, while the needle bar may be adjusted as desired within its bracket as well as at the desired angle to the 25 standard while the slider may be readily changed and fixed in its position and the standard may also be rotated and slidably moved upon the bolt 21, whereby any desired 30 relative angle and position of the needle point 43 or the head 44 thereof may be obtained.

When desired to mark out or scribe the outline of a groove in a piece of work upon the planer, the lower end of the standard 35 may be projected through the perforation 18 and the bore 12 of the base block and may then be placed against the edge of or in one of the grooves of the planer bed and with the needle point properly adjusted, the base 40 block may be then slid along for scratching a line with the needle point and by shifting the needle or the standard other lines may be drawn parallel thereto. It will also be evident that a curved line may be drawn in 45 a similar manner which will be parallel to the edge of a curved or a circular object, while the base may be readily slid along or upon a shaft when the standard is projected through the base in the manner described. 50 The invention therefore affords a convenient device employable as a surface gage, a level, a trammel gage and a scribing gage and is adapted for the use of machinists in the placing and gaging of work when using 55 a planer or lathe as well as in erecting machinery and other articles.

While the form of the invention herein shown and described is what is believed to be the preferred embodiment thereof, it is nevertheless to be understood that minor 60 changes may be made without departing from the spirit and scope of the invention as set forth in the claims.

What I claim as new is:—

1. A surface gage comprising a base block 65 having an opening therethrough and an annular socket concentric with said opening at the upper end thereof, a disk revolvably mounted within said socket and having a central perforation in alignment with said opening, spaced ears upon said disk at opposite sides of said perforation, a longitudinally slotted standard pivotally and slidably mounted between said ears at a point above the perforation of said disk, and a 70 needle bar adjustably positioned upon said standard.

2. A gage comprising a base having an opening therethrough, a disk revolvably mounted upon said base and having a perforation in alignment with the said opening, spaced ears upon said disk adjacent the said opening, a bolt spanning the space between the said ears, a standard having a longitudinal slot therethrough slidably and 85 rotatably mounted upon the said bolt, a set nut upon said bolt, a slider adjustably positioned upon the said standard and a needle bar slidably and revolvably mounted upon 90 said slider.

3. A gage comprising a base having an opening therethrough, a disk anti-frictionally mounted for rotation upon said base and having a perforation concentric with the said opening, a standard having a longitudinal slot therethrough pivotally and slidably mounted upon the said disk, a slider frame adjustably positioned upon the said standard, a bracket rotatably mounted upon one side face of said bracket, a needle bar 100 slidably mounted within said bracket, and a retaining set screw for said bar.

4. A gage comprising a base block having an opening therethrough and an annular socket concentric with said opening, a graduated disk mounted rotatably within the said socket, a graduated ring upon said block, overlapping the said disk, a standard pivotally and slidably mounted upon the said disk, said disk having a perforation therein 105 aligning with the said opening, said standard provided with a longitudinal slot forming opposite side portions provided with graduations, a frame slidably mounted upon the said standard, a needle bar pointed at one end and headed at the other, said needle bar being slidably and rotarily mounted upon the said frame and having graduations upon one side thereof.

In testimony whereof I affix my signature 120 in presence of two witnesses.

THOMAS KOPINSKI.
